LIGHTING FIXTURE ASSEMBLY

Leo Geenens, Katonah, N. Y.

Application August 11, 1947, Serial No. 767,891

10 Claims. (Cl. 240—51.11)

1

This invention is an improved mounting for fluorescent lamps of the long, slim tubular type. The improved mounting is particularly advantageous where a number of lamps are mounted in a long line, in groups connected in series, for lighting an elongated passage, such as a vehicular or railway tunnel, corridors, loading platforms, and large rooms, although its use is not restricted to any particular locality.

The mounting is particularly advantageous, however, for lighting a vehicular tunnel and the invention will be particularly described in connection with such use.

In the prior art, tunnels have been lighted by providing inset cast iron boxes, set into the roof or sidewall of the tunnel, the outer or exposed parts being usually of bronze, serving to support protecting sheets of glass, above or behind which incandescent lamps are mounted. This type of fixture must be watertight, involving the use of gaskets. Such a fixture is quite expensive; moreover, in replacing the incandescent lamp, the protecting glass sheet must be removed, which is a time consuming operation. The same applies where fluorescent lamps are merely substituted for the incandescent lamps using appropriate inset boxes. In busy vehicular tunnels, traffic flows twenty-four hours a day, and it is important that the lamps be replaced quickly, so that traffic is not blocked any longer than necessary.

One of the important objects of the invention is to provide an improved fixture for fluorescent lamps, one of the advantages of such a fixture being that it does not need to be recessed into the roof or sides of a tunnel and does not require the use of sheets of glass covering recessed lamps, nor the use of gasketed joints, thereby saving a great deal of expense.

Another important object is to provide a fluorescent tube fixture wherein an old or defective light may be removed and replaced in a few seconds.

In vehicular tunnels, greasy dust tends to deposit on the walls and fixtures and it is customary to run pump trucks through the tunnel from time to time, which throw sprays of cleansing solution, which is corrosive, and streams of rinsing water on the walls and fixtures for clearing away the dust.

Another important object of the invention is to provide a fixture which while more exposed than a recessed fixture, will be cleaned by such a stream, has a minimum of metal parts subject to corrosion and will not be short circuited or otherwise damaged by the cleansing solution or the rinsing water coming in contact with the high potential terminals inside the fixture.

Another important object of the invention is to provide a fixture comprising essentially a

2

lighting cartridge including a tubular jacket usually made of glass with closure plugs and electrodes therein. This cartridge is removably supported from end brackets secured to the wall or ceiling, so that by simply inserting the lighting cartridge in its place between the brackets, the electrical connections are made and the lamps are lighted. The lamps used are usually tubular vapor lamps having a single contact at each end but lamps with double contacts at each end may also be accommodated.

Another important object of the invention is to provide a fixture in which a unitary lighting cartridge composed of a jacket and one or more fluorescent lamps operatively mounted therein, can be removed and replaced in a few seconds by another similar cartridge, in the event that the lamps in any cartridge had become defective.

Another important object of the invention is the provision of a fixture which will require, when a number of them are mounted in a long line, a minimum number of supporting brackets; this is advantageous inasmuch as each bracket constitutes a break in the continuity of the line of light and each additional bracket involves additional cost. The lighting cartridge of my improved fixture permits the lighting of several lamps of conventional length in series, or specially built long lamps, without the use of intermediate supporting brackets in the wall or ceiling, thereby greatly increasing the spacing of the brackets and producing a more nearly continuous line of light.

Another important object of the invention is to provide a fixture in which the lamps are protected from breakage, from flying objects such as pieces of automobile tire chains or from flapping tarpaulins carried on tops of vehicles, or through blasts of air, such as occur when large vehicles travel at high speed in vehicular tunnels. The conventional tubular lamps themselves unenclosed in a jacket are too delicate to resist these conditions, particularly when long lamps are mounted horizontally and supported from their ends.

Another important object of the invention is to provide a fixture in which water and cleaning solutions can flow freely through the high voltage contact-making parts, without causing an electric current to flow through the water or solution to the workman applying them.

Another important object of the invention is to provide a fixture in which a means is provided to prevent electric shocks to the workmen handling the lighting cartridge.

Another important object of the invention is to provide a fixture in which the fluorescent lamp is enclosed in a chamber, thereby protecting it from the cold air in winter and thereby greatly increasing the light output of the lamp.

Further advantages of structure and operation will be described in connection with the accompanying drawings, showing the invention in more detail, wherein:

Figure 1 is a side view, partly in section, on a reduced scale, of several of the cartridges mounted in line in their respective brackets, forming the subject matter of this invention.

Figure 2 is a side elevation of the fluorescent light unit and their cooperating bracket, on a larger scale, with parts in section, showing the transformer with high and low voltage terminals and cooperating with the adjacent ends of two cartridges.

Figure 3 is a vertical cross section on line 3-3 of Figure 2.

Figure 4 is a vertical cross section on line 4-4 of Figure 2.

Figure 5 is a vertical cross section on line 5-5 of Figure 2.

Figure 6 is a vertical cross section on line 6-6 of Figure 2.

Figure 7 is a vertical cross section on line 7-7 of Figure 1.

Figure 8 is a horizontal section on line 8-8 of Figure 2.

Figure 9 is an elevation of a half portion of the high voltage terminal insulator.

Figure 10 is an elevation of the other half portion of the high voltage terminal insulator.

Figure 11 is an elevation of the grounding shim.

Figure 12 is an elevation of the high voltage terminal.

Figure 13 is a side view of the lighting cartridge.

Referring now to these drawings, the fixture comprises a metal or plastic bracket 2, with bare or painted or porcelain enameled surfaces, anchored to the cable box 2a embedded in the roof or walls of a tunnel, for example, by bolts 4.

The housing includes a box 6 for the transformer 8. A power cable 9 is connected to bolt 10a passing through a porcelain insulator 10b, being secured to box 6 by a screw 10c passing through the insulator and engaging a securing washer 10d on the inside of box 6. Bolt 10a is connected to one lead 10 of the primary of the transformer, the return lead 10' being connected to a bolt similar to 10a, also mounted in insulator 10b and in turn connected to a continuing portion 9a of the power cable leading to the next adjacent fixture. The power cables may be housed in pipes 11.

The low voltage or grounded lead 12 of the transformer is electrically connected to a clamp 12a, the clamp being electrically connected to box 6, and carrying a grounding cable 12b, this grounding cable being secured to clamp 12a, in electrical contact with cable box 2a. The cable box 2a is grounded in any convenient way, as by connecting it to a bare grounding cable (not shown), extending along from one cable box to the next.

The high voltage lead 13 of the transformer is connected to the fluorescent lamps, as will be described below.

The drawing shows a series connection of the primaries of successive transformers as used in a series system of power distribution, but the fixtures will operate likewise if the primaries of successive transformers are connected in parallel in a multiple system of power distribution.

The housing 2 also includes an open-ended, horizontal chamber 16. This chamber has an inwardly extending annular rib 18 defining an opening 20. Seated against flange 18 is an as-

bestos washer 22 and a metal grounding shim 24, grounded by wire 12d, Fig. 3, connecting it to grounding clamp 12a. Seated against this shim is a high voltage terminal insulator 26 for the high voltage conductor 28, energized by its connection to high voltage lead 13 of the transformer. Conductor 28 terminates in contact block 30. A high voltage terminal insulator 32 is held against the other side of the conductor by bolts 33 secured to an asbestos strip 33a and is provided with a convex annular projecting insulating plug 34, having a hole 36 therein.

Seated against the other side of flange 18 is a grounding spring 40, secured to the outer end of which is a low voltage terminal cup 42 provided with a low voltage contact pin 44 anchored by nut 46. Spring 40 and cup 42 may be connected by wire 41 to grounding clamp 12a or otherwise grounded, the low voltage of the secondary of the transformer being grounded, through 12b and 12c, as already described.

The lighting cartridge, for quick connection and disconnection with the foregoing bracket, will now be described. This lighting cartridge comprises a straight tubular jacket 50 of glass or other transparent or translucent material, within which is coaxially housed one or more fluorescent tubes 52, of the hot or cold cathode type, having a single electrode 54 at one end and a single electrode 56 at the other end of the container. Tubes 52 are positioned in their jacket by annular holders 58 and 60 at the ends of the jacket and by similar holders at the connection point of two lamps when several lamps are used in series.

At the high voltage end, jacket 50 has threaded thereon a metal cap 62 having a terminal flange 64 for holding an insulating closure plug 66, which has an annular flange for seating against the end of 50. Closure plug 66 is recessed as at 68 to fit over, but in spaced relation with, projection 34, to define therebetween a drainage passage 70 for water or cleaning solution. Closure plug 66 is provided with a high voltage electrode pin 72, which connects the high voltage terminal 30 with terminal 54 of the fluorescent tube.

At the low voltage end of the lighting cartridge, jacket 50 has threaded thereon a metal cap 74, having a terminal flange 76 for holding an insulating closure plug 78, which has an annular projection 80. Closure plug 78 is centrally recessed to receive the low voltage contact pin 44, which bears against electrode 82 in the recess. Electrode 82, at its left end, engages with a threaded contact washer 84, in contact with connecting spring 86 which in turn is in contact with holder 60 which contacts with the electrode 56 of the fluorescent tube.

It will be apparent that the low voltage connections just described apply to a second jacket 50 and light 52 of the next aligned lighting cartridge, and that the described connections are duplicated at the right hand end (not shown) of jacket 50 and light 52 shown at the right of Figure 2.

It will be seen that to insert a lighting cartridge, the right hand end must be inserted in cup 42 and pushed to the right to compress spring 40 until the left hand end of the lighting cartridge has cleared the lower edge of cavity 16 after which the left hand end can be lifted and inserted over plug 34. If, however, the left hand end of the lighting cartridge was inserted first over plug 34 and an operator would hold his hand

over insulator 78, his hand would not come in contact with electrode 82 because of the projection 88 and therefore he would not complete the circuit of the lamps and be subjected to an electric shock.

An accumulation of dust, carbon, moisture, etc., on the exterior of jacket 50 of the light cartridge might form a conductive layer that would be dangerous to an operator grasping jacket 50 of the light cartridge for removing it. In order to avoid this, bracket 2 is provided with a resilient grounding spring 90, anchored by screw 92, which bears against the metal cap 62 of the lighting cartridge, as shown at the right of Figure 2. Any stray voltage emanating from pin 72 over the surface of insulator 86 is thereby grounded. This spring is preferably made of phosphor-bronze.

The described lighting cartridges are preferably mounted in a continuous straight line and two or more may be in series, as in Figure 1.

In operation, with a lighting cartridge in operative position, as in Figure 2, a defective light may be quickly removed by an operator who grasps the cartridge, moves it to the right against spring 40, sufficiently to disengage and clear the interfitting insulator 34 and 66, to clear the right hand end of cavity 16 and of course, breaking the high voltage connection between electrode 72 and contact 30. The cartridge is then moved downwardly and pulled out of low voltage terminal cup 42 and clear of the left hand edge of cavity 16 in the adjacent bracket. A new cartridge may be inserted by reversing these operations. These operations may be performed in a few seconds, an important consideration in vehicular tunnels where traffic should be interrupted for as short a time as possible.

This quick change is made possible by the improved lighting cartridge, comprising the jacket 50, the fluorescent tube mounted therein, and the contact electrodes at each end of the cartridge; it is also made possible by the improved bracket, built as described, to cooperate with such improved lighting cartridge.

Lighting cartridges and brackets as described may be washed and cleaned by a pressure stream of cleaning solution and water, without danger of grounding through the stream. The right hand end of cavity 16 and the zig-zag passage 70 impede the flow towards high voltage contact 72 but any water or solution which may reach this contact will drain away. Any stray high voltage current is grounded by the grounding spring 90 and the grounded metal shim 24.

With the cartridge of this invention, shown in its entirety in Fig. 13, the relatively fragile light tubes 52 are always protected by the heavier protecting jacket 50. The rigidity afforded by the heavier jacket 50 provides a cartridge of substantial length, much longer than could be spanned by an ordinary fluorescent lamp; a single jacket 50 therefore carries several lamps in line, as shown in Fig. 13.

A particularly important feature of the jacket 50 is that it encloses an annular insulating body of air surrounding the lamps, serving to keep them relatively warm, which is especially valuable in winter, because the lighting effect of fluorescent lamps is greatly diminished at low temperatures.

The cartridges of the present invention may be assembled in a straight line, to provide a continuous line of light, from one end of a traffic tunnel to the other; this is a distinct improvement over spaced lights, where the rapidly passing ve-

hicles cause intermittent light and dark flashes as the vehicles pass by such lights; with the substantially continuous light afforded by this invention, such light and dark flashes are eliminated. Any moisture is drained away through passage 70. Any stray high voltage is grounded through end cap 62 and contact 90.

With the unitary cartridge and cooperating fixture of the present invention, a defective or worn-out lamp may be very quickly replaced, with a minimum of interruption to traffic, a feature of particular importance in a traffic tunnel.

While the preferred embodiment of the invention has been described in detail, it should be understood that the invention is not limited to the exact details shown, but may be carried out in other ways.

I claim as my invention:

1. A lighting cartridge for fluorescent lamps, comprising a translucent tubular jacket, a closure plug of insulating material for each end of said jacket, a cap detachably secured to each end of said jacket, each cap including means bearing against the outer peripheral portion of said plug, and cooperating with the end of said jacket, for holding said closure plug in place in the end of the jacket, each of said closure plugs being provided with an electrode passing therethrough, a tubular fluorescent lamp mounted in said jacket, and electrodes in the ends of said fluorescent lamp in electrical contact with the electrodes in the plugs in the ends of the jackets, the whole constituting a unitary cartridge which may be handled and installed or removed as a unit in relation to a suitable fixture.

2. A lighting cartridge for fluorescent lamps, comprising a translucent tubular jacket, a closure plug of insulating material for each end of said jacket, a cap detachably secured to each end of said jacket, each cap including means bearing against the outer peripheral portion of said plug, and cooperating with the end of said jacket, for holding said closure plug in place in the end of the jacket, one of said closure plugs being internally recessed in its outside face, an electrode passing through said recessed plug and positioned in said recess, an electrode passing through the other closure plug, a tubular fluorescent lamp mounted in said jacket, and electrodes in the ends of the fluorescent lamp in electrical contact with the electrodes in the jacket, the whole constituting a unitary cartridge which may be handled and installed or removed as a unit in relation to a suitable fixture.

3. In combination, a pair of horizontally disposed, open-ended brackets, a high voltage terminal positioned in each bracket, a low voltage terminal positioned in each bracket, spring means positioned in each bracket and cooperating with its low voltage terminal; lighting cartridges cooperating with said brackets, each lighting cartridge comprising a translucent tubular jacket, a closure plug of insulating material for each end of said jacket, a cap detachably secured to each end of said jacket, each cap including means bearing against the outer peripheral portion of said closure plug and cooperating with the end of said jacket, for holding said closure plug in place in the end of the jacket, each of said closure plugs being provided with an electrode passing therethrough, a tubular fluorescent lamp mounted in said jacket, electrodes in the ends of said fluorescent lamp in electrical contact with the electrodes in the plugs in the ends of the jacket, the whole constituting a unitary car-

tridge which may be handled and installed or removed as a unit by engaging or disengaging one end of said cartridge with or from said spring means in one bracket, said spring means normally serving to hold the other end of the cartridge in engagement with the high voltage terminal in the other bracket.

4. The combination as claimed in claim 3, wherein the cap at the high voltage end of said cartridge is of metal and wherein the adjacent portion of the bracket is provided with means contacting said metal cap for grounding it.

5. In combination, a pair of horizontally disposed, open-ended brackets, a recessed high voltage terminal in each bracket, a high voltage contact set within the recess of each bracket, a low voltage terminal positioned in each bracket, spring means positioned in each bracket and cooperating with its low voltage terminal; lighting cartridges cooperating with said brackets, each lighting cartridge comprising a translucent tubular jacket, a closure plug of insulating material for each end of said jacket, a cap detachably secured to each end of said jacket, each cap including means bearing against the outer peripheral portion of said closure plug and cooperating with the end of said jacket, for holding said closure plug in place in the end of the jacket, one of said closure plugs being internally recessed in its outside face, a first electrode passing through said recessed plug and positioned in said recess, a second electrode passing through the other closure plug, a tubular fluorescent lamp mounted in said jacket, electrodes in the ends of the fluorescent lamp in electrical contact with the electrodes in the jacket, the whole constituting a unitary cartridge which may be handled and installed or removed as a unit by engaging or disengaging one end of said cartridge with or from said spring means in one bracket, said spring means normally serving to hold said first electrode of said cartridge in electrical contact with the recessed high voltage terminal in the other bracket.

6. The combination as claimed in claim 5, wherein the cap at the high voltage end of said cartridge is of metal and wherein the cooperating portion of the bracket is provided with means contacting said metal cap for grounding it.

7. In combination, a pair of horizontally disposed, open-ended brackets, a high voltage terminal, including a convex portion, positioned in one bracket, a low voltage terminal positioned in the other bracket, spring means positioned in said other bracket and cooperating with said low voltage terminal therein; a lighting cartridge comprising a translucent tubular jacket, a closure plug of insulating material for the high voltage end of said jacket, said closure plug having a concave portion, a closure plug of insulating material for the low voltage end of said jacket, a cap detachably secured to each end of said jacket, each cap including means bearing against the outer peripheral portion of said closure plug and cooperating with the end of said jacket, for holding said closure plug in place in the end of the jacket, each of said closure plugs being provided with an electrode passing therethrough, a tubular fluorescent lamp mounted in said jacket, electrodes in the end of the lamp in contact with

the electrodes in said closure plugs, the whole constituting a unitary cartridge which may be handled and installed or removed as a unit by engaging or disengaging one end of said cartridge with or from said spring means in said other bracket, said spring means normally serving to hold the electrode at the opposite end of the tubular lamp in electrical contact with the high voltage terminal in the other bracket, said convex portion of the high voltage terminal interfitting with the concave portion of the closure plug at the high voltage end of the lamp, said convex and concave portions when so interfitted being spaced apart to provide a drainage channel for moisture therebetween.

8. The combination as claimed in claim 7, wherein the cap at the high voltage end of the jacket is of metal and wherein the bracket is provided with means contacting said metal cap for grounding it.

9. In combination, a pair of open-ended brackets, high and low tension terminals carried by each bracket, each high tension terminal comprising a plug made of insulating material and having a convex portion provided with a recess; an electrode in said recess; lighting cartridges cooperating with said brackets, each cartridge including a translucent jacket, a fluorescent tube within said jacket, each jacket being provided with an end closure plug of insulating material having a concave portion, an electrode positioned in the concave portion of said closure plug, a cap, detachably secured to each end of said jacket, each cap including means bearing against the outer peripheral portion of said closure plug and cooperating with the end of said jacket, for holding said closure plug in place in the end of the jacket, said convex and concave portions of said plugs being adapted to fit together in spaced relation with their respective electrodes in contact, and when so interfitted, to define between them a passage for draining away any accumulated moisture.

10. The combination as set forth in claim 9, wherein the cap holding the closure plug in place in the jacket is made of metal, and means carried by each bracket, near its high tension terminal and contacting said metal cap, for grounding it.
